Assistant Examiner — Taylor O Mortorff

(57) **CLAIM**

The ornamental design for dustpan and brush set, as shown and described.

DESCRIPTION

FIG. 1 is a front perspective view of the dustpan and brush set showing my new design in an unpacked position;

FIG. 2 is a top perspective view thereof;

FIG. 3 is a bottom perspective view thereof;

FIG. 4 is a front perspective view the dustpan and brush set in a packed position;

FIG. 5 is a front view thereof;

FIG. 6 is a back view thereof;

FIG. 7 is a left side view thereof;

FIG. 8 is a right side view thereof;

FIG. 9 is a top view thereof;

FIG. 10 is a bottom view thereof; and,

FIG. 11 is a perspective view thereof.

The broken lines in the figures illustrate the portions of the dustpan and brush that form no part of the claimed design.

1 Claim, 11 Drawing Sheets
